US0D1052089S

(12) **United States Design Patent** (10) Patent No.: **US D1,052,089 S**
(45) Date of Patent: ** Nov. 19, 2024

(54) **SMART HEALTH MONITOR**

(71) Applicant: **Fourth Frontier Technologies**,
Bangalore (IN)

(72) Inventors: **Sandeep Sibal**, Mumbai (IN); **Manav Bhushan**, Noida (IN); **Seetharam Rao H M**, Sagar (IN); **Aswin Venu C**, Kozhikode (IN); **Ravali Rupaa Amba**, Bangalore (IN); **Ramesh T Vangal**, Bangalore (IN)

(73) Assignee: **Fourth Frontier Technologies** (IN)

(**) Term: **15 Years**

(21) Appl. No.: **29/810,996**

(22) Filed: **Oct. 11, 2021**

Related U.S. Application Data

(63) Continuation of application No. 29/700,885, filed on Aug. 6, 2019, now abandoned.
